[57] **ABSTRACT**

Salts of orthodialkyl benzene sulfonates have been disclosed as having excellent detergents and biodegradability properties. A process for manufacturing these compounds has also been disclosed. In this process, paraffinic stock of certain carbon atom range is reacted with the aid of a dehydrocyclization catalyst to produce the dialkyl benzene precursors.

ORTHO DIALKYL BENZENE PREPARATION VIA DEHYDROCYCLIZATION PROCESS

This invention relates to compositions having biodegradable detergent properties, more particularly this invention pertains to compositions consisting primarily of orthodialkylbenzene sulfonates having straight saturated hydrocarbon chains; further, the invention also relates to an economical process of obtaining these compositions.

The detergent industry manufactures a large variety of products which find numerous applications.

The most commonly used detergents are of an ionic nature. One distinguishes between alkyl sulfates, which are of limited use due to their liquid state, and alkyl sulfonates and alkyl benzene sulfonates, which are in solid form and are of much wider use. The largest number of detergents is represented at the present time by the alkyl benzene sulfonates which are prepared by alkylation of aromatic hydrocarbons, primarily benzene, by chlorinated paraffins or olefins. The industry is therefore tending to produce more and more straight-chain alkyl benzene sulfates without any tertiary carbon, but isomerization of the alkyl radical is difficult to avoid.

A number of processes have been used which have employed, as starting materials, paraffinic refinery stocks. For the most part, these processes have been based on stocks having a carbon atom range of up to 10. However, these dehydrocyclization processes have not produced the starting materials which could be sulfonated directly to produce detergent base stocks or produce a stock yielding the desired properties and/or biodegradability.

The main difficulty to be overcome in the production of the straight-chain alkyl benzene sulfonates is therefore of an economic nature; to achieve sufficient biodegradability, it is necessary to eliminate from among the isomers obtained by alkylation those in which the hydrocarbon chain is not strictly linear.

The present invention solves the problem of the production of straight-chain alkyl benzene sulfonates and makes it possible to produce them under economic conditions, i.e., substantially only the normal or straight-chain dialkyl benzenes are obtained.

One object of the present invention is to provide industry with new detergents which can be prepared by an economical process.

Another object of the invention is to provide new biodegradable detergents.

Still another object of the invention is to propose a method which makes it possible to produce such detergents easily and at low cost.

The purpose of the invention is compositions having biodegradable and detergent properties, characterized by the fact that they comprise orthodialkyl benzene sulfonates of an alkaline metal or the ammonium ion, the hydrocarbon chains of which are saturated and straight, the sum of the numbers of carbon atoms in said chains being between eight and eighteen, including the terminal atoms.

The orthodisubstituted alkyl benzenes may be prepared in various ways but the work carried out has led to preparation of the saturated straight-chain hydrocarbon orthodialkyl benzene sulfonates by a new process which assures very satisfactory selectivity and yield.

Therefore, another object of the invention is an economical process of manufacturing compositions having

biodegradable, detergent properties, said method being characterized by subjecting normal-paraffin hydrocarbons having a number of carbon atoms of between 14 and 24, terminal atoms included, to passage in a reactor or furnace in the presence of hydrogen over a nonisomerizing cyclizing dehydrogenation catalyst; isolating the single-ring aromatic products obtained; sulfonating them; and neutralizing the resultant sulfonic acids by means of a base.

10 The normal-paraffin hydrocarbons which serve as starting products can be obtained by passing a distillation stream or cut rich in normal paraffins over a molecular sieve.

15 The nonisomerizing cyclizing dehydrogenation reaction can be carried out in the presence of hydrogen; upon entrance into the reactor, the molar ratio of hydrogen to normal-paraffin hydrocarbons is between 0.1 and 10. The temperature therein is within the range of 350°C - 500°C; the temperature depends on the catalyst used and will be given hereafter. During the dehydrogenation, there is a formation of normal olefins, a certain amount of diolefins and aromatic products.

20 The catalyst must be a nonisomerizing cyclizing dehydrogenation catalyst. As a catalyst, Pt-Li-As on alumina support is a suitable composition. Other, suitable and inert supports may be employed with the disclosed catalysts.

25 The single-ring dialkyl aromatic hydrocarbons formed may be extracted in the condensed fraction by suitable means, for instance by passage through molecular sieves, by adsorption over alumina or silica gel or by liquid-liquid extraction by means of a selective solvent.

30 It has been observed that the single-ring aromatic fraction collected is composed practically exclusively of saturated straight-chain orthodialkyl benzenes the sum of the number of carbon atoms in the dialkyl chains of which is between 8 and 18, terminal atoms included, when the initial normal paraffin has a number of carbon atoms of between 14 and 24, terminal carbon atoms included.

35 The aromatic fraction is subjected to a sulfonation which may be carried out with sulfuric anhydride (SO₃) diluted in an inert gas such as nitrogen.

40 The sulfonic acids obtained are then neutralized by a base, for instance soda or ammonia. The resultant sulfonates are then dried.

45 Tests carried out have proven that the compositions thus obtained surprisingly have remarkable properties of detergency and biodegradability.

50 The products of the invention comprise a group of compositions formed primarily of orthodialkyl benzene sulfonates the hydrocarbon chains of which are saturated and straight and which may be represented by the following formula:

55 in which:

60 65 is the benzene ring

M is an alkaline metal or the ammonium ion

R₁ and R₂ are two straight, saturated hydrocarbon chains without any tertiary carbon atom. The sum of the numbers of carbon atoms contained in R₁ and R₂ is equal to n-6; n is the number of carbon atoms which the initial normal paraffin contains; n is between 14 and 24, terminal atoms included.

The accompanying drawing is a diagram which illustrates the two principal stages of the process of the invention, namely the dehydrocyclization of a normal 10 paraffin and the extraction of the orthodialkyl benzenes.

In this embodiment, a fresh normal paraffin having a number of carbon atoms of between 16 and 20, terminal carbon atoms included, which arrives through the line 1 is mixed with recycled products consisting essentially of paraffins and olefins coming from the line 2. This mixture is diluted with hydrogen coming from the line 3 in such a manner that the molar ratio of hydrogen to the normal-paraffin hydrocarbons is close to one. The mixture obtained is introduced at the top of a vertical reactor 4 brought to a temperature of between 15 about 350°C and 450°C. The reactor contains a catalyst consisting of chromium oxide and potassium oxide deposited on alumina in proportions by weight, measured with respect to the alumina, of 2.5 percent for the chromium and 2.2 percent for the potassium. The rate of flow of the normal paraffin measured per unit of reactor volume per hour (v/v/hr) is between 0.5 and 2.5. The products of the dehydrocyclization reaction are recovered in a receiver 5 where the separation of the gases and the liquids takes place. The gases which are composed primarily of hydrogen and cracking products are evacuated through the line 6; the liquids through the line 7 arrive at an extraction column 8 which is filled, for instance, with silica gel. Elution with n-pentane introduced through the line 9 makes it possible to collect via the line 11 the paraffins and olefins which may be recycled; such as, by feeding these to reactor 4 via line 2; further elution with ethyl ether introduced via line 10 makes it possible to recover the aromatic products via the line 12. The latter consist practically entirely of orthodialkyl benzenes with straight saturated hydrocarbon chains the total of the numbers of carbon atoms of which is between 10 and 14, terminal carbon atoms included, depending upon the normal paraffin initially introduced.

The sulfonation and then the neutralization are carried out in accordance with the methods described above.

The invention is furthermore illustrated by the following examples, which are not of a limitative nature.

EXAMPLE I

A stream of normal hexadecane and hydrogen is passed for 6 hours over a dehydrogenation catalyst consisting of chromium oxide and potassium oxide deposited on alumina, the chromium content being 2.5 percent by weight and the potassium content 2.2 percent by weight, both measured with respect to the alumina. The temperature is maintained at 425°C. The rate of flow of the hexadecane is 2 v/v/hr and the molar ratio of hexadecane to hydrogen is 1.

758.6 grams of condensed products are collected from the outlet of the reactor and absorbed on a column which has been previously filled with silica gel. By elution with n-pentane, there are collected 735.5 grams

of a mixture composed of 89.5 percent by weight hexadecane and 10.5 percent by weight olefins. By elution with ethyl ether, there are collected 23.10 grams of aromatic products formed practically entirely of C₁₆ orthodialkyl benzenes having straight saturated hydrocarbon chains for which the sum of the numbers of carbon atoms is 10.

These aromatic products are diluted in normal undecane in such a manner that the concentration by weight of the aromatic products is equal to 15.15 percent. Into this solution which is maintained at 20°C there is introduced a stream of gaseous sulfuric anhydride (SO₃) diluted in nitrogen in such a manner that the molar concentration of the sulfuric anhydride is equal to 3 percent. The stream of gas is maintained for 2 hours; thus, the molar ratio of the sulfuric anhydride used to the orthodialkyl benzenes is 1.2.

The product is neutralized while cold and then decanted. The aqueous phase is treated under reflux with an excess of soda for 1 hour. The organic phase is treated in the same manner with an excess of soda under pressure at 160°C for 1 hour. The two aqueous phases are combined, the excess of soda is neutralized with sulfuric acid and thereupon evaporated until obtaining a dry product which is composed primarily of C₁₆ sodium orthodialkyl benzene sulfonates the hydrocarbon chains of which are straight and saturated.

The detergent properties of the product obtained 30 were compared with those of a current commercial soap by means of the following test. The current commercial soap is of the following composition: sodium salts of fatty acids.

With the product of the invention there was prepared 35 a wash powder having the following composition:

- 20 percent by weight pure detergent product to be tested;
- 18 percent sodium pyrophosphate;
- 5 percent sodium perborate;
- 4 percent colloidal Mg silicate;
- 9 percent anhydrous sodium carbonate;
- 43 percent anhydrous sodium sulfate;
- 1 percent carboxy methyl cellulose.

With this powder two aqueous solutions were prepared, one of 5 g/l of pure detergent and the other of 2 g/l.

With this solution, washings of a fabric impregnated with a standard soiling (fabric marketed under the 50 name "Cotton Soil Test Cloth 51 S 47") were carried out in a "Launderometer" under the following conditions: washing of a sample of 5 g of fabric in 2 liters of solution for 30 minutes at 90°C with agitation with 10 stainless steel balls of about 6 mm in diameter.

In order to determine the detergent power, reflection measurements were carried out by means of an apparatus marketed under the name Photovolt by the Photovol Corporation.

Using the green filter, the following luminances Y were determined:

- Y_e: luminance of the fabric after washing
- Y_s: luminance of the fabric impregnated with the standard dirt

- Y_t: luminance of the support fabric not impregnated with the standard dirt

The detergent power was calculated by means of the following formula:

$$DP \text{ in percent} = (Y_e - Y_s) / (Y_t - Y_s) \times 100$$

The luminances Y_s and Y_t for the fabric used were as follows:

$$Y_s = 28.0$$

$$Y_t = 90.0$$

Under the same conditions, washings of the same fabric were also effected with solutions of 2 g/l and 5 g/l of a current commercial soap as identified above but containing furthermore 1 g/l of anhydrous sodium carbonate.

The results are set forth in Table I below:

TABLE I

	Detergent power in a concentration of 2 g/l	Detergent power in a concentration of 5 g/l	
Sodium orthodialkyl benzene sulfonate	22.6%	24.2%	
Current commercial soap*	17.7%	20.1%	20
* Sodium Salts of fatty acids			

These washing tests show the remarkable detergent properties of the compositions of the invention.

The biodegradable properties of the orthodialkyl benzene sulfonates prepared in the test described above have been determined in the following manner:

For 7 days a microorganism culture was prepared with constant aeration at a temperature of 25°C in a semisynthetic medium containing 20 mg per mil of the product to be tested; thereupon at the end of this time, the same quantity of detergent was again introduced and the test continued until the 10th day. On the 7th and 10th days, analyses were made so as to note the elimination of the products and thus their biodegradability.

The culture broth used in the tests comprises between 2 and 4×10^5 microorganisms per mm³. It was prepared by aerobic fermentation in a nutrient medium rich in microorganisms taken from the water of the Seine River at the point of discharge of the large sewer of Clichy in Paris.

The detergent content of the cultures of microorganisms is determined in accordance with the method of Longwell and Maniecke, the principle of which is as follows: a colored complex is formed with methylene blue; it is extracted with chloroform and a colorimetric measurement made by comparison with a standard product.

The biodegradation rate T_7 at the end of 7 days is given by the following formula:

$$T_7 = (20 - (C_{E7} - C_{t7}) \times 100) / 20$$

in which C_{E7} is the detergent content in the test medium on the 7th day, expressed in mg per mil, and C_{t7} is the detergent content in a control medium on the 7th day, expressed in mg per mil.

In similar manner, the biodegradation rate at the end of 10 days, T_{10} , is given by the following formula:

$$T_{10} = (40 - (C_{E10} - C_{t10}) \times 100) / 40$$

in which C_{E10} is the detergent content in the test medium on the 10th day, expressed in mg per mil, and C_{t10} is the detergent content in the control medium on the 10th day, expressed in mg per mil.

Finally, the actual biodegradability rate T is given by the following formula:

$$T = (0.5 T_7 + T_{10}) / 1.5$$

The results obtained are set forth in Table II.

TABLE II

	CONTROL	Sample No. 17
	Test No. 1	Test No. 2
Concentration of detergent 7th day (ppm)	0.80	3.65 3.9
Biodegradation % 7th day		85.7 84.5
Concentration of detergent 10th day (ppm)	0.65	4.4 3.45
Biodegradation % 10th day		90.6 93
Biodegradability	88.9	90.1
AVERAGE		89.5

EXAMPLE II

The paraffins and olefins coming from the line 11 in the accompanying diagram were passed over the catalyst described in Example I and mixed via line 2 with 33.5 grams of fresh n-hexadecane, namely a total of 169.0 grams of paraffin-olefin mixture passing into the reactor after mixture with hydrogen. The rate of flow of the total charge is 2 v/v/hr, the temperature is 425°C and the molar ratio of hydrogen to hydrocarbon is 1; the time of passage is 1 hour.

There are collected 759.0 grams of liquid products which are adsorbed on a column previously filled with silica gel.

By elution with n-pentane there are collected 717.3 grams of a mixture composed of 86.3 percent paraffins and 13.7 percent olefins by weight. By elution with ethyl ether there are collected 41.7 grams of products composed primarily of straight-chain C_{16} orthodialkyl benzenes.

These products are sulfonated and then neutralized in the manner described in Example I. After drying there is obtained a mixture containing primarily C_{16} sodium orthodialkyl benzene sulfonates with saturated straight hydrocarbon chains, the detergent and biodegradable proportions of which are comparable to those of the compositions of Example I.

EXAMPLE III

A stream of normal hexadecane and hydrogen is passed for one hour over the catalyst used in Example I, heated to 440°C. The rate of flow of the normal hexadecane is maintained equal to 100 g/hr, the v/v/hr of the normal hexadecane is established at 1.0. The rate of flow of hydrogen is 10.6 liters per hour.

The sum of the weights of the cracking products, the dehydrogenation hydrogen and the carbon formed represents 1.4 gram.

The treatment described in Example I applied to the liquid phase produces 75.0 grams of normal hexadecane, 13.6 grams of olefins and 10 grams of aromatic products very rich in C_{16} orthodialkyl benzenes with straight saturated hydrocarbon chains.

These aromatic products are sulfonated by the method set forth in Example I; the molar ratio of the sulfuric anhydride fixed to the orthodialkyl benzene is 1.133.

The sulfonic acids are neutralized by the method described in Example I.

After drying, the mixture contains primarily C_{16} sodium orthodialkyl benzene sulfonates with saturated

straight hydrocarbon chains; the mixture has good detergent and biodegradable properties.

EXAMPLE IV

A stream of n-hexadecane and hydrogen is passed for 2 hours over a dehydrogenation catalyst composed of chromium, copper and potassium on alumina, these metals having been deposited in the form of nitrates, so that after calcination at 800°C there is 4.97 percent by weight chromium, 3.03 percent copper and 1 percent potassium, measured with respect to the alumina. The temperature is maintained at 425°C; the rate of flow of hexadecane is 1 v/v/hr and the molar ratio of hydrogen to hexadecane is 1.

For 100 grams of hexadecane introduced there are collected 12.9 g of olefins, 9.8 g of aromatics, including 6.2 g of orthodialkyl benzenes, and 73.7 grams of unconverted hexadecane. During the dehydrogenation there is no structural isomerization.

The orthodialkyl benzenes obtained are then separated and treated in the manner described in Example I to give C_{16} sodium orthodialkyl benzene sulfonates with saturated straight hydrocarbon chains having detergency and biodegradability properties comparable to those of the compositions of Example I.

EXAMPLE V

A mixture of n-hexadecane and hydrogen is passed for 2 hours over a catalyst consisting of platinum deposited on alumina. The catalyst comprises 0.75 percent by platinum, referred to the alumina, and also 0.5 percent lithium and 0.09 percent arsenic. The temperature being maintained at 400°C, the rate of flow of the hexadecane being 1 v/v/hr, and the molar ratio of hy-

drogen to hexadecane being 1.0, there are collected for 100 grams of n-hexadecane introduced 69.0 grams of unconverted hexadecane, 12 grams of aromatics, including 7.4 grams of orthodialkyl benzenes, and 12.6 grams of olefins. During the dehydrogenating reaction there is not noted any structural isomerization of the olefin and the alkyl benzenes recovered have only straight chains.

These orthodialkyl benzenes are then sulfonated and neutralized in the manner described in the preceding examples in order to give the detergent compositions according to the invention.

We claim:

1. A process for preparing ortho-dialkyl benzenes which comprises:
  - a. passing a stream consisting of normal paraffin hydrocarbons having from 14 to 24 carbon atoms, together with from 0.1 to 10 mols of hydrogen per mol of normal paraffin, into a reaction zone in the presence of a supported, non-isomerizing, cyclicizing dehydrogenation catalyst selected from the group consisting of (1) chromium oxide and potassium oxide on alumina, and (2) the product produced by the calcination of the nitrates of chromium, copper and potassium on alumina;
  - b. reacting said paraffin therein at a temperature of from 350° to 500°C and removing from said reaction zone a hydrocarbon mixture rich in orthodialkyl benzenes having a total of from eight to 18 carbon atoms in the alkyl chains and;
  - c. separating said dialkyl benzenes from other components in the mixture removed from said reaction zone.
